United States Patent Office.

GEORGE GILL, OF TAUNTON, MASSACHUSETTS, ASSIGNOR TO REED & BARTON, OF SAME PLACE.

Design No. 4,696, dated March 7, 1871.

DESIGN FOR A PEDESTAL FOR A CAKE-DISH.

The Schedule referred to in these Letters Patent and making part of the same.

To all persons to whom these presents may come:

Be it known that I, GEORGE GILL, of Taunton, of the county of Bristol and State of Massachusetts, have invented or produced a new or ornamental Design for the Pedestal of a Cake-Dish or Tazza; and do hereby declare the same to be described as follows, and to be represented in the accompanying drawing, which exhibits such pedestal in elevation.

In such drawing—

A denotes the base;

B, the shaft; and

C, the capital of the pedestal.

The shaft is cylindrical or tapering, and near its top is provided with a milled bead, a.

On and abutting against the flanks of the shaft is a series of leonine heads, b, and legs c, formed and arranged as represented, each leg having a leaved front.

The shaft and the feet of the legs spring from a cylindrical platform, d, composing part of the base, the remainder of which, with the capital, is formed in manner as represented. The base and the capital are to be circular in horizontal section; or, if preferable, each or either may be elliptical in such section.

From each of the lions' heads a queue, e, is extended upward against the shaft.

I claim—

The design for a pedestal, as described and represented.

GEORGE GILL.
